United States Patent Office

Des. 211,075
Patented May 21, 1968

211,075

PANTY GIRDLE

Sallyann Z. Salisky, Garfield, N.J., assignor to Sarong, Inc.,
Dover, Del., a corporation of Delaware

Original design application Apr. 13, 1966, Ser. No. 1,872, now Patent No. 208,900, dated Oct. 17, 1967. Divided and this application Feb. 23, 1967, Ser. No. 8,452

Term of patent 14 years

(Cl. D2—4)

Fig. 1

Fig. 2

Fig. 3

FIG. 1 is a front elevational view of a panty girdle showing my new design;

FIG. 2 is a side elevational view thereof;

FIG. 3 is a rear view thereof;

FIG. 4 is a front elevational view of a second embodiment of the design shown in FIG. 1, wherein the ornamental motif is on the front only;

FIG. 5 is a side elevational view of the embodiment of FIG. 4;

FIG. 6 is a front elevational view of a third embodiment of the design shown in FIG. 1 wherein the ornamental motif is repeated on the side;

FIG. 7 is a side elevational view of the embodiment of FIG. 6; and

FIG. 8 is a rear elevational view thereof.

This is a division of application Ser. No. D.1,872 filed Apr. 13, 1966 now Patent No. D.208,900.

I claim:

The ornamental design for a panty girdle, as shown and described.
